UNITED STATES PATENT OFFICE.

JOHN HENRY BLAIR, OF CHICO, CALIFORNIA, ASSIGNOR OF ONE-SIXTH TO EDWARD C. BINET, OF OROVILLE, CALIFORNIA, ONE-SIXTH TO C. W. EASTIN, OF SAN FRANCISCO, CALIFORNIA, ONE-SIXTH TO T. W. RINGLAND, OF OAKLAND, CALIFORNIA, AND ONE-HALF TO J. W. CHARGE, OF BUTTE COUNTY, CALIFORNIA.

PITMAN-WHEEL.

1,264,260.

Specification of Letters Patent. Patented Apr. 30, 1918.

Application filed November 25, 1914. Serial No. 873,996.

To all whom it may concern:

Be it known that I, JOHN HENRY BLAIR, a citizen of the United States, residing at Chico, in the county of Butte and State of California, have invented certain new and useful Improvements in Pitman-Wheels, of which the following is a specification.

This invention relates to transmission mechanism, and more particularly to that 10 type of such mechanism known as pitman or trammel wheels.

One object of the invention is to provide a trammel wheel having improved means for adjusting and guiding the sectors so as to 15 insure their proper relation. Another object is to provide an improved means of connecting the pitman rod with the slides whereby greater strength is obtained.

With the above and other objects in view, 20 and to improve generally upon the details of construction of such apparatus, the invention consists in the arrangement and combination of parts hereinafter described and claimed, and illustrated in the accompanying drawing, in which:

Figure 1 is a front elevation of my improved trammel or pitman wheel, showing one end of the pitman rod connected therewith;

Fig. 2 is a section on the line 2—2 of Fig. 1, looking in the direction of the arrow; and,

Fig. 3 is a section on the line 3—3 of Fig. 1, looking in the direction of the arrow.

Referring to the drawings in detail, my improved trammel wheel comprises a disk 1, shown as solid, and preferably provided on its rear face with a central boss 2 in which the end of the driving shaft 3 is secured. Surrounding this disk is a rim 4, which is rigidly secured to the disk in any desired way, preferably by shrinking, after the manner of a tire. This rim is of greater width than the thickness of the disk, and projects beyond the front face thereof a considerable distance, as clearly shown in Figs. 2 and 3.

Mounted upon the front face of the disk 1 within the rim 4 are the four sectors or quadrants 5, spaced apart to form the intersecting grooves or guideways 6. The combined thickness of these sectors and the disk is approximately equal to the width of the

rim so that the rim is substantially flush with the face of the wheel on both sides. 55

The edges of the sectors 5 are under-cut to form grooves 7, adapted to retain the slides 8 in the guideways, such slides being provided with co-operating ribs or flanges 8'. Each slide 8 carries a pivot pin 9, and the 60 pins 9 extend through a boss 10, formed on the ends of the legs 11 of a Y-shaped pitman rod 12. The other end of the rod 12 is preferably bi-furcated, as shown at 13, to receive a wooden or other suitable bar, (not 65 shown) which extends to the device to be operated. A link 14 connects the pivot pins 9, and is secured in position by nuts 15, which hold the parts in assembled relation. It will be seen that this link 14 acts as a 70 brace or tie-rod to prevent the spreading of the legs of the Y-shaped pitman rod. This results in an exceptionally strong and rigid construction.

In addition to the advantages resulting 75 from the mechanical strength of the above described structure, there is another distinct advantage which may be mentioned. It will be noted that the pivot pins 9 lie on a line at right angles to the axis of the pitman rod 80 12. Owing to this arrangement, it is not necessary that the pitman rod operate in a plane parallel with the wheel, as in prior devices, but such pitman rod may extend at an angle to the plane of the wheel without 85 causing binding of the slides 8 in the guideways, suitable flexible joints being in this case provided at the points 9. This feature is of particular importance in agricultural 90 machines, such as reapers and mowers, for which this trammel wheel is especially suitable.

In order to permit adjustment of the sector-shaped blocks 5, they are secured to the disk 1 by means of tap bolts 16, which are 95 set into the blocks and work through elongated openings or slots 17, formed in the disk 1. It will be evident that by slightly loosening these bolts, the sectors may be adjusted as desired.

In order to facilitate fine adjustments, set screws 18 are provided, two for each sector, such screws extending through the rim 4 and bearing upon the outer edges of the sectors. It is apparent that by loosening the bolts 16, and then turning the screws 18,

the sectors 5 may be adjusted with great accuracy.

I also provide means for maintaining the sectors in proper relation when being adjusted. To this end, there are formed on the meeting faces of the disk 1 and sectors, co-operating ribs and grooves as indicated at 19, and most clearly shown in Fig. 2. As illustrated, the ribs are formed upon the disk and the grooves in the sectors, but obviously this arrangement might be reversed. These radially disposed ribs and grooves insure the sectors being held in true radial position at all times, and thus preserve absolute uniformity in the width of the guideways throughout their length. This is essential to the successful working of a device of this character.

In operation, as the wheel turns, the slides 8 traverse the guideways 6 in such a manner as to cause two complete strokes of the pitman rod for every revolution of the wheel.

What I claim is:

1. The combination with a trammel wheel

Copies of this patent may be obtained for five cents each, by addressing the "Commissioner of Patents, Washington, D. C."

having intersecting guideways, of a slide 25 working in each guideway, and a pitman rod having a Y-shaped end, each leg of which is connected with one of said slides.

2. The combination with a trammel wheel 30 having intersecting guideways, of a slide working in each guideway, a pitman rod having a Y-shaped end, each leg of which is pivoted to one of said slides, and a link connecting such pivots to prevent spreading.

3. The combination with a trammel wheel 35 having intersecting guideways, of a slide working in each guideway, and a pitman rod having a pivotal connection with said slides, the pivot points lying on a line substantially at right angles to the axis of said 40 pitman rod.

In testimony whereof I have affixed my signature, in presence of two witnesses.

JOHN HENRY BLAIR.
